Primary Examiner — Sandra Snapp*Assistant Examiner* — Ieisha N Price(74) *Attorney, Agent, or Firm* — Dorton & Willis, LLP(57) **CLAIM**

The ornamental design for a chainsaw, as shown and described.

DESCRIPTION

FIG. 1 is a front isometric view of the chainsaw according to the invention.

FIG. 2 is a rear isometric view of the chainsaw according to the invention.

FIG. 3 is a front view of the chainsaw according to the invention.

FIG. 4 is a right side view of the chainsaw according to the invention.

FIG. 5 is a rear view of the chainsaw according to the invention.

FIG. 6 is a left side view of the chainsaw according to the invention.

FIG. 7 is a top view of the chainsaw according to the invention; and,

FIG. 8 is a bottom view of the chainsaw according to the invention.

The broken lines in the drawings illustrate portions of the chainsaw and form no part of the claimed design.

1 Claim, 8 Drawing Sheets(56)
